UNITED STATES PATENT OFFICE.

DE VER H. WARNER, OF BRIDGEPORT, CONNECTICUT, ASSIGNOR TO THE WARNER BROTHERS COMPANY, OF SAME PLACE.

DESIGN FOR A STUD OR BUTTON FOR GARMENT-SUPPORTERS.

SPECIFICATION forming part of Design No. 33,772, dated December 25, 1900.

Application filed March 21, 1900. Serial No. 9,616. Term of patent 14 years.

To all whom it may concern:

Be it known that I, DE VER H. WARNER, a citizen of the United States, residing at Bridgeport, in the county of Fairfield and State of Connecticut, have invented and produced a new and original Design for Studs or Buttons for Garment-Supporters, of which the following is a specification.

My invention relates to a new and original design for studs or buttons for garment-supporters, of which the following is a specification, reference being had to the accompanying drawings.

Figure 1 of the drawings is a plan view of a stud and support embodying my new design, and Fig. 2 is a side view of the same.

As shown in the drawings, my new design consists in a stud or button for a garment-supporter having an enlarged cylindrical shank and a relatively small head having a circular periphery, the head resting upon and above a circular flange placed between the head and the shank. The stud is mounted on a looped support or base *a*, as shown.

The essential features of my new design consist in a stud having a relatively large cylindrical shank *b* and a smaller head *d* of a relatively dark appearance resting upon and above a rounded circular flange *c*, larger in diameter than *b* or *d* and of a relatively light or bright appearance as compared with the head *d*. The head *d* rests upon and is framed by the flange *c*.

Having described my invention, what I claim as new, and desire to secure by Letters Patent, is—

The design for a stud or button for garment-supporters, substantially as herein shown and described.

In witness whereof I have hereunto signed my name in the presence of two witnesses.

DE VER H. WARNER.
